LAWN SPREADER FOR FERTILIZER, SEED OR THE LIKE

Simon Bylsma and Emil A. Madison, Sac City, Iowa,
assignors to Remcor Inc., Sac City, Iowa, a corporation
of Iowa

Filed Oct. 1, 1964, Ser. No. 31,981

Term of patent 14 years

(Cl. D35—2)

Fig. 1

Fig. 2

FIG. 1 is a side elevational view of a lawn spreader for fertilizer, seed or the like showing our new design;

FIG. 2 is a front elevational view of the same;

FIG. 3 is a side elevational view of the same looking at the side opposite from the side shown in FIG. 1;

FIG. 4 is a rear elevational view of the same; and

FIG. 5 is a top plan view of the same.

We claim:

The ornamental design for a lawn spreader for fertilizer, seed or the like, substantially as shown.
